COMBINED ROTARY LAPPING AND WASH MACHINE

Stanley E. Franklin, Wilmington, Calif., assignor to
Marine Pumps, Inc., Wilmington, Calif., a corporation
of California

Filed Feb. 18, 1959, Ser. No. 54,668

Term of patent 14 years

(Cl. D37—1)

Des. 188,765

PAGE 2

Fig. 2.

Fig. 1 is a front elevational view of a combined rotary lapping and wash machine embodying my new design;
Fig. 2 is a right side elevational view;
Fig. 3 is a top plan view thereof;
Fig. 4 is a left side elevational view; and
Fig. 5 is a top perspective view thereof.
I claim:

The ornamental design for a combined rotary lapping and wash machine, substantially as shown.
